Atty

UNITED STATES PATENT OFFICE.

WILLIAM S. LUCKETT, OF CHESTNUT HILL, PENNSYLVANIA.

GOLFING OUTFIT.

Application filed February 24, 1922. Serial No. 538,923.

To all whom it may concern:

Be it known that I, WILLIAM S. LUCKETT, a citizen of the United States, residing at Chestnut Hill, in the county of Philadelphia 5 and State of Pennsylvania, have invented certain new and useful Improvements in Golfing Outfits, of which the following is a specification.

The present invention has reference 10 broadly to improvements in golfing outfits and more particularly relates to a golf bag and support therefor.

The invention contemplates as its principal object to provide a device of the above 15 character wherein the bottom of a self sustaining bag is designed to be detachably connected to a ground engaging support for the purpose of maintaining the bag in an upright supported position, thereby affording 20 convenience for a player who is without the assistance of a caddy.

More particularly the invention embraces 25 the provision of a device of the above mentioned character wherein the construction of the detachable connection and the support are novel and in addition are respectively 30 capable of being readily assembled and applied where desired for use.

It is a more specific object of the invention 35 to provide a golf bag the bottom of which may be detachably engaged with a prong or other member for penetrating the ground, the walls of the bag being sufficiently reinforced to withstand the shock 40 incident to the engagement of the prong with the ground.

Among the other aims and objects of this 45 invention may be recited the provision of a device of the above character with a view to compactness and wherein the number of parts are few, the construction simple, the cost of production low and the efficiency high.

Further objects as well as the nature, 50 characteristic features and scope of the invention will be more readily understood from the following description taken in connection with the accompanying drawings and pointed out in the claim forming a part of this specification.

The invention is clearly illustrated in the accompanying drawings, in which:—

Figure 1 is a side elevation of the bag and support.

Figure 2 is an enlarged fragmentary vertical section through the lower portion of the bag and support, and

Figure 3 is a side elevation of a slightly modified form of support.

Similar characters of reference are employed throughout several views to indicate corresponding parts.

Referring now, more particularly, to the accompanying drawings there is provided a golf bag designated generally by the numeral 1 mainly of conventional design while

detachably associated with the bottom of the bag is a ground engaging support indicated in its entirety by the numeral 2. In connection with the bag it may be stated the body may be suitably reinforced as by light metal tubes 3 or the like which act to render the bag sufficiently rigid to withstand the shock incident to the engagement of the support with the ground. A relatively rigid

annular rim portion 3' is connected with the upper edge of the body of the bag. In addition the cup-like bottom 4 of the bag is provided with means forming a part of a detachable connection, in the present instance consisting of an integral central socket 5 which is preferably threaded for association with the support.

The support comprises generally a bag receiving plate 6, the upper face of which is provided with suitable engaging means, such as a stud 7, the stud forming a part of the detachable connecting means and like the socket 5 is desirably threaded for detachable connection with the socket. Supporting prongs or legs 8 form suitable ground engaging means for the support and insure of the supporting of the bag.

In Figure 3 there is employed only one prong or leg 8' on the plate 6', this being of a larger size than the prongs or legs 8 to insure of proper supporting.

In use a golfer, who is without the assistance of a caddy, may connect the support 2 to the bag 1 and carry the bag in the usual manner until he reaches a position where it is desired to swing a club, whereupon the upper part of the bag is gripped in one hand and moved downwardly so as to jab or cause the prongs to engage the ground. Upon release of the bag the same will be supported owing to the rigidity afforded the bag by the tubes 3. As apparent the bag may be

2
moved from place to place about a golf course and in this manner afford a material convenience to the golfer.

Although I have shown and described a 5 plug and socket as a detachable connection, it is, of course, apparent that any equivalent means may be employed for this purpose.

It is believed in view of the foregoing that 10 a further detailed description of the operation of the invention is entirely unnecessary. Likewise, it is believed that the advantages of the invention will be readily apparent.

Having thus fully described the invention, 15 what is claimed as new and desired to be secured by Letters Patent is:—

A golf bag comprising a body formed of 20 flexible material, a relatively rigid annular rim portion connected to the upper edges of the flexible body, a cup like rigid bottom receiving the lower end of the body and hav-

ing its central portion thickened and provided with an open ended screw threaded socket, a circular supporting plate of a circumference similar to the circumference of the bottom, a central up-standing exteriorly threaded stud carried by the plate for detachable engagement with the socket for releasably maintaining the plate in intimate contact with the bottom, prongs depending from the under surface of the plate for penetrating the ground, and a series of reinforcing rods secured to the flexible body and extending vertically thereof and positioned between the rim portion and the bottom to 30 render the body self-sustaining and to permit of the bag with the plate attached thereto to be thrust against the ground so that the prongs enter therein.

25 In testimony whereof I affix my signature. 35

40 WILLIAM S. LUCKETT.
